RAYMOND P. MORSE, OF SCARSDALE, NEW YORK, ASSIGNOR, BY MESNE ASSIGNMENTS,
TO CANTILEVER CORPORATION, A CORPORATION OF NEW YORK.

SHOE-FITTING DEVICE.

Application filed January 14, 1921, Serial No. 437,185. Renewed August 20, 1927.

This invention relates to shoe fitting devices, and has for its object to provide a device whereby shoes can be more accurately fitted than with the devices at present available for this purpose.

At present, the common method is to use a length scale, usually graduated in sizes instead of inches, and the width being either determined by guess or by measuring the flat width of the foot. Such methods are objectionable because of inaccuracy and possibilities of error, and also because they do not take into consideration either the length from ball to heel or the varying arch curvature of the foot in different persons. The result is that the ball or large joint of many customers is not properly fitted, because of inadequate appliances, and the customer is frequently inclined to blame the maker of the shoe for unsatisfactory results.

I have made an extensive investigation into this subject and have found that it is possible to largely eliminate these objections by a properly constructed fitting device. I have further found that a better fit is obtained by determining the length of the shoe as a function or proportion of the length of the foot from the ball to the heel, and that this measurement of length from the ball to the heel should follow the surface of the foot so as to take the curvature of the arch into consideration, it being well known that there is the widest variation in arch curvature.

While the first essential in properly fitting a shoe is to select the proper length of a shoe to locate the ball, the second essential is to provide sufficient length in the shoe from ball to toe to accommodate the toes, which is also indicated. The third essential is to determine the required width of shoe, which is accomplished by a device indicating the actual width of a shoe of given length required to fit the foot. Having determined the length of shoe required to fit the foot, the width measuring device indicates by circumferential measurement of the actual foot the correct width of shoe required in that length for the foot. This gives the width of shoe required for the actual foot in that length of shoe already determined.

To accomplish these objects, I have devised the method and apparatus herein dis-

closed wherein the length to be fitted is based upon the distance from the ball or large joint of the foot to the heel following the surface of the foot so as to allow for arch curvature, and the width is subsequently ascertained, according to the size of the actual foot for that length. It is also desirable in a device of this character to provide for different lasts and also for men's and women's sizes, which differ in measurements for given sizes and widths according to recognized trade standards.

An apparatus of my invention is shown in the accompanying drawings wherein—

Figure 1 is a plan view;

Figure 2 is a plan view with the top removed;

Figure 3 is a vertical section on the line 3—3 of Figure 2;

Figure 4 is a transverse section on the line 4—4 of Figure 2;

Figure 5 is a section on the line 5—5 of Figure 2, and

Figure 6 is a detail view.

The device comprises a foot support or base in the form of a box, as 1, having a top plate 2 on which is mounted a casting 3 containing recesses 4 for the large joint or ball of each foot. The recesses are formed and shaped to generally fit the ball of the foot. Anchored to the casting 3, as at 6, is a flexible resilient arch conformator 7 which is slidably supported on the heel block 8, sliding under a plate 9. Each arch conformator 7 may carry at its rear end the size scales 10 for men's sizes and 11 and 12 for women's sizes, the scales 11 and 12 being, for example, for different women's lasts. As herein shown, the scale 11 is for a last of one height of heel and the scale 12 for another last of different height, or there may be other differences in these lasts as desired. 13 represents a heel gage carrying the pointer 14 cooperating with the scales 10, 11, 12, the gage 13 being mounted on a vertical stud 15 carried by plate 16 sliding on rods 17, the stud 15 working through a slot 18 in the plate 2 and central plate 9 as shown in Figure 1. 19 is a guide plate between the two heels carried by the heel block 8. The heel block 8 may be made of such height as desired, or may be omitted entirely.

It will be seen from the foregoing that the arch conformator 7 will carry the scales 10,

11, 12 backward as the foot is pressed thereon, while the ball remains stationary in the recess 4, and the heel gage 13 is then brought up into gentle contact with the heel. The 5 plate 16 is connected by link 20, lever 21 pivoted at 22 and link 23 to a second sliding plate 24, also mounted on the rods 17. The plate 24 carries a stud 25 working through slot 26 in the support and carrying the toe 10 gage plate 27. The toe gage plate 27 is provided with graduations as shown for lasts corresponding with the heel scales 10, 11, 12. The plate 27 forms a check on the length as determined by the gage 13, and enables the 15 salesman to be certain that such length will not be too short for the foot being fitted; as in rare cases it may happen that the length of the foot from ball to toe is too great for a particular last otherwise best fitting the 20 foot. This toe plate also enables the salesman to explain to the customer where the toe of the shoe will come. It will further be observed that the position length of the 25 foot and of the toe gage is determined as a function of the length of the foot from ball to heel by reason of the difference in the 30 lengths of the arms of lever 21. While this principle of measuring for shoes is herein specifically described with reference to first 35 measuring the foot from ball to heel, the principle could be carried out by measuring the distance from ball to toe in special instances, but it would not be generally desirable because the main part of the foot to be fitted is that from ball to heel with the arch curvature correction.

Figure 4 shows the width measuring device associated with the ball recesses 4, comprising a strap 28 with gage 29 and a central strap 30 carrying one or more width scales, as shown in Figure 1, according to different lasts for men and for women. The strap 30 passes down between the two ball recess portions to a slide 32 on transverse bar 33. 34 is a lever pivoted at 35 to the cover plate 2 and having one end connected by link 37 with slide 16 and the other end 38 in the path of lug 39 on slide 32. The arms of lever 34 are proportioned so that the desired ratio 40 of movement is effected, so that the lever end 38 will stop the strap 30 by contact with lug 39 to determine the proper width for a given length as determined by the position of the heel gage.

If the ball measure of a certain foot is, for example, $7\frac{1}{2}$ inches, and the size or length of last required is 4, a B wide shoe is required; but if the size or length required is 5, an A wide shoe is needed. Therefore, the ball measuring strap is limited by a positive stop, which stop is controlled and regulated by the same apparatus which measures the length. In operation, the strap 28 with gage 29 is laid flat on the foot, and strap 30 pulled until stopped by lug 39, or until tight on

the foot, and laid over gage 29, giving the proper width for each length. The length and width thus determined correspond to the length and width of a standard shoe last.

The lasts upon which shoes are made are of certain standard sizes and widths, and the grading or linear difference in measurements between sizes (or lengths) of any certain width, or between widths of any certain size, is constant. To determine the proper size shoe to fit a particular foot, that shoe must be selected which has been manufactured on the particular size and width of last most nearly corresponding to that foot.

In addition to this difference in linear 80 dimensions in the various sizes of any last, the ratio between ball to heel and ball to toe lengths in different sizes of a last is a constant. This relation is represented by the 85 lengths of the arms of lever 21 in Figure 2. Therefore when the heel plate indicates on the scale the proper length to fit the foot from ball to heel, the toe gage will show the 90 position of the toe of the last, indicating whether that size correct for ball to heel measurement will give sufficient toe room.

As will be seen, the device is shown for measuring both feet, in case there is a material difference, but the single strap 30 is so arranged relatively to the toe strap 28 95 as to operate with either. In either case, the same numbers are used on the drawing for duplicate parts.

It is believed that the objects and advantages of the invention will be understood 100 from the foregoing description and also that the method is applicable to other specific forms of apparatus than that herein disclosed, and that the apparatus may be modified in various particulars without departing 105 from the scope of the appended claims.

What I claim is:

1. The method of determining the length 110 of a shoe to be fitted which comprises determining the length of a foot from the ball to the heel including a correction for the curvature of the foot arch as a fraction of the total length.

2. The method of determining the length 115 of a shoe to be fitted which comprises determining the length of a foot from the ball to one end of the foot, including a correction for the curvature of the foot arch as a fraction of the total length.

3. A shoe fitting device comprising means 120 for determining the length of a foot including a correction for arch curvature, and means controlled by the length determining means for determining the circumferential width.

4. A shoe fitting device comprising a foot supporting base having a recess for receiving the ball of a foot, a resilient arch conformator arranged to slide rearwardly according to the curvature of the arch and 130

carrying a scale, and a heel gage movable to contact with the heel and cooperating with said scale.

5. In a shoe fitting device the combination with a foot supporting base, of a foot length measuring means on the base including longitudinal slidable gage for co-operation with an end of the foot, a yielding arch conformator on the base, and a foot length size 30 indicator responsive to movements of said arch conformator and said end gage.

6. A shoe fitting device comprising a foot supporting base having a recess for the ball of a foot, a yielding arch conformator having its heel end slidable on the base, and carrying a scale, a heel gage sliding on the base and cooperating with said scale, a toe gage, and means connected with said toe gage to move the same with said heel gage.

20 7. A shoe fitting device comprising a foot supporting base having a recess for the ball of a foot, a yielding arch conformator mounted on and having its heel end slidable on the base, and carrying a scale, a heel gage sliding on the base and co-operating with said scale, a toe gage on said base, means connected with said toe gage to move the same with said heel gage but in the op-

posite direction, a movable foot width gage, and means controlled by the heel gage for 30 adjusting the width gage.

8. In a shoe fitting device, a base to support a foot, a yielding arch conformator on said base, and foot length determining means also on said base and responsive to 35 the amount of deformation of said conformator when displaced by arch pressure of a foot being measured.

9. In a shoe fitting device, a base for supporting two feet side by side, with gage 40 straps on said base, one for each foot, and a width measuring strap located between said gage straps and operable with either gage strap.

10. The method of determining the size 45 of a shoe for a given foot which comprises determining the length of the foot by measurement and determining the circumferential width of the foot as a function of said determined length including arch curvature of the foot.

Signed at New York city, in the county of New York and State of New York this 8th day of January, A. D. 1921.

RAYMOND P. MORSE.
